Primary Examiner — Paula Allen Greene(74) *Attorney, Agent, or Firm* — Crowell & Moring LLP;
John C. Freeman(57) **CLAIM**

The ornamental design for a wind hood holder for microphones as shown and described.

DESCRIPTION

FIG. 1 is a front elevational view of a wind hood holder for microphones showing our new design;
 FIG. 2 is a bottom plan view thereof;
 FIG. 3 is a top plan view thereof;
 FIG. 4 is a right elevational view thereof;
 FIG. 5 is a left elevational view thereof;
 FIG. 6 is a rear elevational view thereof; and,
 FIG. 7 is a top, front, right perspective view thereof.
